(57) **CLAIM**

The ornamental design for a rope pet chew, as shown and described.

DESCRIPTION

FIG. 1 is front and top perspective view of a first embodiment of a rope pet chew according to the new design; FIG. 2 is a front elevation view of the embodiment of FIG. 1;

FIG. 3 is a rear elevation view of the embodiment of FIG. 1;

FIG. 4 is a left side elevation view of the embodiment of FIG. 1;

FIG. 5 is a right side elevation view of the embodiment of FIG. 1;

FIG. 6 is a top plan view of the embodiment of FIG. 1;

FIG. 7 is a bottom plan view of the embodiment of FIG. 1;

FIG. 8 is a bottom perspective view of the embodiment of FIG. 1;

FIG. 9 is front and top perspective view of a second embodiment of a rope pet chew according to the new design;

FIG. 10 is a front elevation view of the embodiment of FIG. 9;

FIG. 11 is a rear elevation view of the embodiment of FIG. 9;

FIG. 12 is a left side elevation view of the embodiment of FIG. 9;

FIG. 13 is a right side elevation view of the embodiment of FIG. 9;

FIG. 14 is a top plan view of the embodiment of FIG. 9;

FIG. 15 is a bottom plan view of the embodiment of FIG. 9;

FIG. 16 is a bottom perspective view of the embodiment of FIG. 9;

FIG. 17 is front and top perspective view of a third embodiment of a rope pet chew according to the new design;

FIG. 18 is a front elevation view of the embodiment of FIG. 17;

(Continued)

FIG. 19 is a rear elevation view of the embodiment of FIG. 17;
 FIG. 20 is a left side elevation view of the embodiment of FIG. 17;
 FIG. 21 is a right side elevation view of the embodiment of FIG. 17;
 FIG. 22 is a top plan view of the embodiment of FIG. 17;
 FIG. 23 is a bottom plan view of the embodiment of FIG. 17;
 FIG. 24 is a bottom perspective view of the embodiment of FIG. 17;
 FIG. 25 is front and top perspective view of a fourth embodiment of a rope pet treat according to the new design;
 FIG. 26 is a front elevation view of the embodiment of FIG. 25;
 FIG. 27 is a rear elevation view of the embodiment of FIG. 25;
 FIG. 28 is a left side elevation view of the embodiment of FIG. 25;
 FIG. 29 is a right side elevation view of the embodiment of FIG. 25;
 FIG. 30 is a top plan view of the embodiment of FIG. 25;
 FIG. 31 is a bottom plan view of the embodiment of FIG. 25;
 and,
 FIG. 32 is a bottom perspective view of the embodiment of FIG. 25.

The broken lines in the drawings illustrate portions of the rope pet chew that form no part of the claimed design. Additionally, the rope pet chew is shown with a symbolic break in the third and fourth embodiment in its length. The appearance of the rope between the break lines from no part of the claimed design.
